APPARATUS FOR MAKING EMULSIONS OF BITUMINOUS MATERIALS

Matthew Griffin O'Neil, Dallas, Tex., assignor to Donald O'Neil, Dallas, Tex.

Application June 10, 1936, Serial No. 84,489

1 Claim. (Cl. 259—95)

The present invention relates to the production of emulsions, and to improved apparatus for emulsification. It finds particular application in the emulsification of a bitumen in an aqueous medium containing a soapy, or other, dispersing or emulsifying agent.

More particularly the invention is concerned with an improved process and apparatus for making emulsions of asphalt in water.

An object of the invention is to provide an improved process and apparatus for making emulsions of bituminous materials in water which emulsions are highly stable and in which the emulsified material is extremely finely divided and of uniform particle size.

A further object of the invention is to provide a process of emulsification which is carried out without the use of beaters or similar types of mixing units.

According to the process of the present invention, the material to be emulsified is gradually added, in small increments, to a circulating stream of dispersion medium (water, or aqueous fluid, including a suitable emulsifying agent) continuously led from and delivered to a main body of the dispersion medium, successive portions of the stream, under considerable pressure and at high velocity, being continuously injected into portions of the stream at materially lower pressure, thereby utilizing the cutting and disintegrating forces of the high velocity stream portions to reduce the particle size of the dispersed phase, the circulation and injection being continued until the particle size of the dispersed phase of the resulting emulsion has been reduced to the desired degree. As the dispersion medium I may, and preferably do, employ hot, relatively soft water containing dissolved therein a suitable amount of an emulsifying agent (e. g., a soap). I may continue the circulation and injection of the liquid after the desired proportion of material to be emulsified has been introduced thereto. Also, after the desired amount of material to be emulsified has gradually been introduced into the continuous phase and dispersed therein, in the manner above described, I may and preferably do continue the disintegration of the particles of the dispersed phase by continuing the circulation and injection while progressively increasing the velocity of the injected stream portions, or their pressure, or both. This latter I may effect by progressively decreasing the size of the openings through which the stream portions are forced, under pressure, into the stream portions of lower pressure.

The process hereinafter will be described in greater particularity in conjunction with a preferred form of apparatus for carrying it into effect, which apparatus also forms a part of the invention.

This apparatus is illustrated in the accompanying drawing, wherein:

Fig. 1 is a plan view of the assembled equipment embodying the invention;

Fig. 2 is a side elevation thereof;

Fig. 3 is a vertical sectional view through the emulsifying unit, taken on the line 3—3 of Fig. 1;

Figure 4 is a sectional view on the line 4—4 of Figure 3;

Figure 5 is a sectional view on the line 5—5 of Figure 3; and

Figure 6 is a sectional view on the line 6—6 of Figure 4.

Referring now more particularly to the drawing, A is a tank containing asphalt to be emulsified. Suitable heating means, such as steam coils, not shown, are provided to maintain the asphalt at the proper temperature, it being desirable to add the asphalt hot. A water container W is provided, the same being calibrated in gallons and, as will become apparent hereinafter, determines the degree of concentration by the rising level of the emulsion, hence no measuring meters are necessary. The container is provided also with suitable means, not shown, for maintaining the proper temperature of liquid in the container.

The tank A is connected by a conduit 11b to a pressure pump 9, there being a control valve 11a to govern the delivery of material from the tank A. A conduit 11c leads from container W and connects with the conduit 11b on the intake side of the pump 9, a control valve 11a being located in the conduit 11c. A suitable motor M is provided for driving the pump 9.

The delivery side of the pump 9 is connected by a pipe 14 to an emulsifying unit 8 which consists of a metal shell, preferably cylindrical in shape, and divided by a horizontal partition wall 19 into a large upper compartment 17 and a smaller lower compartment 18. The partition wall 19 is provided with a number of threaded openings into which the lower ends of perforated pipes are threaded.

These pipes are divided into sets, and designated as 12, 15 and 16 having different sized perforations, those in pipes 15 being smaller than in pipes 12, and those in pipes 16 being smaller than in pipes 15.

The perforated pipes are disposed in the com-

partment or chamber 17 and are partially covered by rotary sleeve valves 20 which fit over the upper ends of the pipes, the sleeve valves having closed upper ends which serve as caps for closing the upper ends of the tubes. It will be noted that the valve sleeves 20 are imperforate except for an elongated passage or slot 20a in the side thereof, and also that the perforations in the tubes 12, 15 and 16 extend only part way around the tubes so that they may be partially or wholly covered by the imperforate portion of the sleeve valves 20 to regulate the flow from compartment 17 to compartment 18.

The sleeve valves 20 are provided with stems 15 extending through the top of the unit 8 and handles 12a, 15a and 16a are mounted on the stems for operating the valves.

By reference to Figs. 1 and 3, it will be noted that the pipe 14 delivers fluid from the pump 9 20 to the chamber 17 and that the pipe 14a leads from the chamber 18 back to the tank W.

In carrying out the process of the present invention utilizing the apparatus described, assuming that it is desired to produce 2,000 gallons of 25 an emulsion having an asphaltic content of 50 per cent, with all valves closed, 1,000 gallons of hot soft water is placed in the calibrated tank W. An emulsifying agent such as a soap solution is added to the water in an effective amount, and 30 the mixture is maintained at a temperature of not less than 180° F. The pump 9 is then started into operation and the valve 11a is opened to allow the mixture of water and emulsifier to flow into the chamber 17, through the perforations in the 35 pipes 12 which will be opened into the discharge chamber 18 and back to the tank W.

The valve 11 is then opened gradually to admit a relatively small stream of the hot asphalt from the tank A into the circulating stream of water 40 and emulsifying agent, a proportion of one part of asphalt to about three parts of water being preferable. The resulting mixture of materials is then forced by the pump 9 into the chamber 17 under high pressure and through the perforations 45 in the pipes 12 where it is impacted under high pressure into the moving stream or body of the constantly increasing dispersed phase at a lower pressure in the pipes 12 and discharge chamber 18, from which latter the mixture is finally 50 returned to the tank W. As the materials are constantly recirculated as the addition of the asphalt proceeds, the concentration of the dispersed phase will constantly increase until the desired concentration is reached.

55 The desired concentration is determined by the rising level of the emulsion in the container W and having been reached and the supply of asphalt stopped by closing valve 11, the valves on pipes 12 will be closed and one of the succeeding series 15, 15 or 16, 16 selected, each of which have smaller perforations than the preceding series.

The selection of the series of perforated tubes to be used will be governed by the hardness of the bitumen used and of the degree of heat contained 60 in it. The object being to carry the process to that point where the cutting and disintegrating action

of the numerous high-pressure sprays will have reduced, by their discharge under pressure into an area of lower pressure, the particle size of the dispersed phase to the degree required.

It will be seen that the pressure in the emulsifier 5 8 will be controlled within the limits of the power of the pump by making use of a greater or less number of the perforations in the tubes during the operation.

The pressure on chamber 18 and pipe 14a is 10 maintained relatively low by reason of their having a greater carrying capacity than the ability of the pump to produce. This in turn keeps the same low pressure inside of the perforated tubes through which the materials are forced. 15

From the description of the process, it will be seen that I carry out the following steps which I claim to be new and necessary for the results to be obtained.

First: The materials are combined at a low concentration and gradually increased to the desired concentration over a considerable period of time, during which time the materials are continually in motion and being disintegrated by a plurality of high pressure streams impinging on each other 25 and into the moving stream of emulsion as the same is being formed.

Second: This process accomplishes the accurate proportioning of the ingredients through the use 30 of calibrated containers.

Third: I avoid the use of beaters or stirring blades, thereby preventing an increase of particle size by compaction of the heavier materials with the blades or with each other. The release 35 of the combined liquid materials through successively smaller nozzles and from a relatively high pressure to a lower pressure disintegrates the particles into smaller units.

While a preferred form of the invention has been shown and described, it is to be understood 40 that various modifications in the details of the apparatus and steps of the process may be resorted to without departing from the spirit of the invention within the scope of the appended claim.

What I claim is:

In apparatus for emulsification, a liquid tank, means for establishing a closed circulating stream of liquid from and to said tank, said means including a pump and emulsifier unit comprising a receptacle, a partition wall dividing said receptacle into high and low pressure compartments, a plurality of perforated pipes mounted in said partition wall extending into said high pressure compartment and opening at one end into said low pressure compartment, means for closing the other end of said pipes and for regulating the flow of liquid through said perforations in the pipes, said means comprising sleeve valves mounted on said pipes, said sleeve valves being imperforate and having an elongated slot in one side thereof, said perforations in said pipes extending only part way around the pipes, a connection from said pump to said high pressure compartment and a connection from said low pressure compartment back to said liquid tank.

M. GRIFFIN O'NEILL.
